LAMP.

1,027,196.

Specification of Letters Patent.

Patented May 21, 1912.

Application filed March 16, 1911. Serial No. 614,783.

To all whom it may concern:

Be it known that I, JOHN H. GEORGE, a subject of the King of Great Britain, residing at Bridgeport, in the county of Fair-
5 field and State of Connecticut, have invented certain new and useful Improvements in Lamps, of which the following is a specification.

This invention relates to lamps and par-
10 ticularly to lamps of the type commonly employed on automobiles, motorcycles and the like.

The object of the invention is to effect certain improvements in the construction
15 of lamps of this general type with respect particularly to the manner of mounting the reflector within the casing of the lamp.

The breakage of the reflectors of lamps has heretofore been a source of frequent an-
20 noyance to users of motorcycles, automo-
biles and the like. Much of this breakage has been due to the expansion and contrac-
tion of the reflector as the latter is heated
25 up by the flame of the lamp and cools after
the flame is cut off, the mounting of the re-
flector being such that this expansion and
contraction have subjected the reflector to
30 excessive strain. This invention is directed
primarily to mounting the reflector in such
a manner as to materially reduce the dan-
ger of breakage resulting from strains of
35 this character. Furthermore, in accord-
ance with the invention this object is at-
tained in a construction possessing the de-
sirable characteristics of ready remova-
40 bility of the reflector, marked simplicity
and low manufacturing cost.

The invention will be described in con-
nection with the accompanying drawings,
45 which show the preferred embodiment
thereof and in which—

Figure 1 is a side elevation of a lamp having my improved form of reflector sup-
port, the view being broken away and sec-
45 tioned in part, Fig. 2 is a back view of the reflector, and Fig. 3 is a central vertical section showing the parts on an enlarged scale.

Referring to these drawings, Fig. 1 shows
50 a lamp of a form now in common use, this being merely typical of the type of lamps to which the invention is specially appli-
cable. The lamp has a body 1 cylindrical
in its general form and closed at the rear
55 by a back 5, these parts being preferably

made of sheet-brass. The front of the body is closed by a hinged door 2 having a suitable lens therein. Within the body is a burner adapted to burn acetylene gas, the latter being supplied to the burner by a 60 tube 3. At the sides of the body are brackets 4 adapted to coat with the support for the lamp in the usual manner. The reflector 6 is mounted within the rear portion of the body of the lamp; it is preferably of 65 the usual form, having its front and rear surfaces curved about different centers.

I will now describe my improved means
for mounting the reflector and point out the
advantages obtained thereby.

70

The reflector 6 is provided with a back-
ing 7 of sheet-metal. This backing is formed from a circular piece of metal which is spun over the reflector so that it lies flat against the back of the reflector with its 75 edge 8 turned over the edge of the reflector forming a flange which holds the backing and reflector together securely. At a plu-
rality of points about the center of the backing, the metal thereof is cut as shown 80 in Fig. 2 and the cut portions are turned outwardly to form tangs 9 integral with the backing. These tangs are utilized to se-
cure to the backing 7 a threaded collar or sleeve 10. This collar is shown as fitting 85 snugly within the four tangs 9 and in-
teriorly threaded, and it is securely held by the tangs, as by being soldered thereto.

The back 5 of the lamp has a circular opening cut in the center thereof and an 90 exteriorly threaded member 11 projects through this opening. Member 11 is rig-
idly secured to the back 5; to facilitate this, it is provided with an enlarged head 12 which may be soldered to the back 5. The 95 portion of the member 11 projecting within the body of the lamp is threaded and of a size to be received in the collar 10. With the parts thus constructed, the reflector is mounted in position by turning the reflec-
tor so that the collar 10 screws upon the threaded end of member 11. With the parts assembled in this manner, it will be seen that the reflector is supported upon the casing of the lamp at a point near the 100 center of the reflector rather than around the periphery thereof. Also, it will be noted that the reflector is spaced from the casing near the periphery so that there may be free circulation of air around the reflec- 105 110

tor and therefore unequal expansion and contraction is less apt to occur. The reflector may be conveniently and quickly removed whenever such removal becomes desirable for inspection or cleaning. Furthermore, but a small number of parts are employed and these may be manufactured and assembled at small cost.

Having now described my invention, 10 what I claim as new therein and desire to secure by Letters Patent is as follows:—

In a lamp, the combination of a casing, a reflector therein, a backing for the reflector formed from a single piece of sheet-metal 15 and having its edge turned over the edge of the reflector, integral projections on said

backing near the center thereof, a threaded member secured to said projections, and a threaded member projecting through an opening in the back of the casing and secured to the casing, said threaded members being adapted for coaction in removably mounting the reflector upon the back of the casing, and said member secured to the back of the casing forming the sole support for 25 the reflector, substantially as set forth.

This specification signed and witnessed this 7th day of March, 1911.

JOHN H. GEORGE.
